UNITED STATES PATENT OFFICE.

PAUL McDORMAN, OF DAYTON, OHIO, ASSIGNOR TO THE NATIONAL LAUNDRY MACHINERY COMPANY, OF DAYTON, OHIO, A CORPORATION OF OHIO.

ELECTROLYTIC CELL.

1,001,876.

Specification of Letters Patent. Patented Aug. 29, 1911.

Application filed December 29, 1910. Serial No. 599,846.

To all whom it may concern:

Be it known that I, PAUL McDORMAN, a citizen of the United States, residing at Dayton, in the county of Montgomery and State 5 of Ohio, have invented certain new and useful Improvements in Electrolytic Cells; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to new and useful improvements in electrolytic cells for the decomposition of a solution of a salt to form a bleaching liquid and the like.

The object of the invention is to provide 20 means in an electrolytic apparatus which prevents the current passing through the liquid around the electrodes, thereby compelling the current to pass through the liquid directly between the electrodes, and securing the greatest amount of decomposition.

The improvements and advantages obtained thereby will be more full described hereinafter, in connection with the accompanying drawings.

30 Referring to said drawings, Figure 1 is a top plan view of my improved electrolytic apparatus. Fig. 2 is a section of the same on the line *a—a* of Fig. 1. Fig. 3 is a section of the same on the line *b—b* of Fig. 1.

35 And Fig. 4 is a view showing a modified form of inlet ducts for the cell proper.

In the drawings, 1 designates an outer vessel provided with cleats 2, Figs. 2 and 3, which support a plate 3. Mounted on the 40 plate 3 is an inner vessel 4 which forms the electrolytic cell proper. The sides of the cell or inner vessel 4, are provided with grooves 5 which receive the vertical edges of a lower series of non-conducting plates 6, an intermediate series of electrodes 7 such as carbon or graphite, and an upper series of non-conducting plates 8. The compartments formed by the plates 6 and 8, and the electrodes 7, communicate with the bottom 45 of the outer vessel 1 through an elongated opening 9 in the bottom of the inner vessel 4, and openings 10 in the plate 3. The said compartments also communicate with the outer vessel 1 at the top through openings 50 11 in the sides of the inner vessel. The

openings 11 are provided with tubes 12, which lie in grooves or troughs 13 in plates 14 supported on cleats 15 on the outer vessel 1. The openings 11 and tubes 12 are arranged staggered relatively to each other, each alternate compartment being provided with an opening 11 and a tube 12 on the same side of the inner vessel 4. At each end of the vessel or cell 4 is a pole piece 16, which, when the device is in use, are connected in 60 an electric current. The outer vessel is supplied with a solution of salt, the upper level of which is slightly below the top of the plates 14, which allows the liquid to enter the compartments between the plate 6 and 8 65 and the electrodes 7 in the inner vessel or cell 4, to the same height. The liquid may consequently flow into the inner vessel 4 through the openings 10 and 9, and out of said vessel through the openings 11, tubes 12 70 and grooves 13. The entire device, with the exception of the electrodes 7 and pole pieces 16, is made of insulating material, and when the electric circuit is closed, the current will flow from one pole piece 16 to the other 75 80 through the electrodes 7 and the solution between them. The current passing through the liquid, decomposes the salt therein and forms a bleaching liquid. During this decomposition, a gas is liberated that lowers 85 the weight of the liquid, which constantly flows upwardly out of the compartments through the openings 11, the liquid, meanwhile, flowing into said compartments through the openings 9 and 10, as shown 90 by the arrows in Fig. 2. A circulation of the liquid is therefore produced, which is necessary to the practical operation of the device.

The decomposition is most effectually produced between the electrodes 7, and as the liquid in flowing from one compartment to the other passes through an elongated channel or passage-way, practically all of the current will pass through the electrodes, as 95 the resistance of the liquid in the tubes 12, grooves 13, outer vessel 14, and openings 9 and 10 is necessarily much greater than the liquid immediately between the electrodes. As the openings 11 are arranged staggered, 100 the current will not pass around any one electrode 7, as the resistance of the liquid in the tubes 12 and grooves 13 is greater than the liquid immediately between the electrodes. By increasing the circulation of the 105 110

liquid, it is possible for all said liquid to pass between the electrodes which results in greater efficiency as well as greater strength in making the bleaching liquid. An increased circulation of the liquid when flowing out of and into the compartments is secured by uniting a series of tubes 17 in the openings 10 of the vessel 4. These tubes may, of course, be angular or straight. The circuit of travel of the liquid is thereby materially lengthened.

From the above description and the accompanying drawings, it will at once be seen that the construction is devoid of any difficult ports or passages leading either to or from the inner vessel, and thus the cost as well as the work of making the apparatus is reduced to a minimum. The outlet tubes 12 are easily inserted in their respective openings in the upper portions of the side walls of the inner vessel, and the channel plates or troughs 14 are likewise placed in position with little or no effort.

I claim:

1. In an electrolytic apparatus, outer and inner vessels, the inner vessel being provided with openings along the upper sides thereof which communicate with the interior sides of the outer vessel, said inner vessel also provided with an opening which communicates with the outer vessel at the bottom, electrodes mounted in said inner vessel and forming compartments with which the openings along the upper sides of said inner vessel communicate, a series of outwardly and laterally extending tubes mounted in the openings in the sides of the inner vessel, and grooved plates mounted along the upper portions of the sides of the inner vessel and receiving said tubes, substantially as described.

2. In a device of the type specified, an outer vessel, an inner vessel mounted therein, electrodes mounted in said inner vessel and forming compartments, pole pieces mounted at the end of said inner vessel, said inner vessel being provided with openings

along the upper edges of the sides thereof which communicate with the outer vessel and with the compartments, said inner vessel also provided with an elongated opening at its bottom which communicates with said compartments, a plate mounted below said inner vessel and provided with openings which communicate with the outer vessel at the bottom and with the opening in the bottom of the inner vessel, tubes mounted in the openings in the sides of the inner vessel, plates mounted along the upper edges of the sides of the inner vessel, said plates provided with grooves which receive said tubes, whereby, when both vessels are filled with liquid, and the pole pieces are connected in an electric circuit, the resistance of the liquid in the outer vessel will cause the current to pass through the electrodes.

3. In an electrolytic apparatus, an outer vessel, an inner vessel mounted therein, said inner vessel provided with openings along its upper sides which communicate with the outer vessel, and an elongated opening in its bottom, a plate below the bottom of said inner vessel with a series of openings communicating with the interior of the inner vessel through the elongated opening in the bottom thereof, a series of tubes secured within said openings in said plate and extending in proximity to the bottom of the outer vessel, electrodes mounted in the inner vessel and forming compartments with which the openings in the inner vessel communicate, outwardly and laterally extending tubes mounted in the openings in the sides of the inner vessel, and grooved plates mounted on the sides of the inner vessel and receiving said tubes, substantially as specified.

In testimony whereof I affix my signature, in presence of two witnesses.

PAUL McDORMAN.
